N. PETERS. Photo-Lithographer, Washington, D. C.

UNITED STATES PATENT OFFICE.

JOHN GREEN, OF ELMIRA, MICHIGAN.

BOB-SLEIGH.

SPECIFICATION forming part of Letters Patent No. 415,196, dated November 19, 1889.

Application filed August 31, 1889. Serial No. 322,552. (No model.)

To all whom it may concern:

Be it known that I, JOHN GREEN, a citizen of the United States, residing at Elmira, in the county of Otsego and State of Michigan, have invented certain new and useful Improvements in Bob-Sleighs; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to certain new and useful improvements in that class of bobsleds which are intended especially for use in moving lumber and heavy logs and timber; and it has for its object to generally improve upon the construction, as well as to cheapen, simplify, and render more efficient in operation this class of vehicles.

To these ends and to such others as the invention may pertain the same consists in the peculiar construction and in the novel combination, arrangement, and adaptation of parts, all as more fully hereinafter described, and specifically defined in the appended claims.

The invention is clearly illustrated in the accompanying drawings, which, with the letters of reference marked thereon, form a part of this specification, like letters of reference indicating like parts throughout the several views, and in which drawings—

Figure 1 is a top plan view of the same. Fig. 2 is a central vertical section. Figs. 3 and 4 are details more particularly hereinafter referred to.

Reference now being had to the details of the drawings by letter, A and A' represent the forward and rear bobs, respectively. Each of the runners B is made, preferably, of a single piece, the same being cut away in such a manner as to give the desired curvature for the runner and leaving the raised portion B', which serves as a knee, over the top of which knee is secured a metallic plate B², upon which plate is designed to rest the end of the transverse timber C, which timber is retained in place by means of the bolts C', which are passed downward through the metallic brace-

strip C², and after passing through said cross-timber extend a short distance into the knee. The bolts C' are designed to be fastened into the brace-strip C² by entering the brace-strip from the under side and being headed down on top. The brace-strip C² is made of spring metal, and is passed over the end of the transverse timber, and has its ends secured to the upper face or edge of the runner by means of the bolts D, passed through the elongated slots C³ in the brace-strip, said bolt being passed upwardly from the lower face of the runner, the lower end of the bolt being provided with an enlarged head D', which is countersunk in the lower face of the runner, and the bolt is retained in place by the shoe D². The upper end of the bolt D is screw-threaded to receive a nut D³. By this construction it will be readily seen that the brace-strip will serve to securely retain the parts in place, and at the same time it is adapted to give slightly without breaking upon occasions of sudden strain or jolt.

The vertical bolts or rods C', being retained loosely within the holes in the knee, may be readily lifted out when the brace-strip is removed, which may be done at any time by simply removing the nuts D³. Any one of the runners may thus be quickly and easily detached from the vehicle when it may be found desirable or necessary to remove the same for the purpose of repair or other purpose.

To the front edge of the roll E of the rear bob are secured the metallic strips E', which strips are bent back over the ends of the roll, and their free ends are bent to form the loops E², adapted to engage the corresponding hooks E³ upon the inner faces of the forward ends of the runners. These hooks are secured to the runners in such positions as to permit the loops to be hooked over the same only when the roll is turned into such a position as to throw the reach which is attached thereto into a substantially vertical position, so that the parts cannot be detached until the front end of the reach has been detached from its connection with the forward bob. This dispenses with the roller rod and braces commonly used.

The roll F, to which the neap or pole F' is secured, is attached to the forward bob in the

manner described for securing the roll to the rear bob, thus dispensing with the use of the roller rod and braces commonly used.

Upon the front edge of the roll E is secured 5 the block E⁴ by means of the metallic strip E⁵, the rear ends of which strip are passed through the said roll and are secured in place by means of nuts, as shown, the body of the strip being passed around the outer edge of 10 the block.

The reach G is made of a heavy strip of sheet metal, the rear end of the reach being secured to the upper face of the roll and block by means of bolts G', as shown, a series of 15 holes g being provided in the reach, so that the same may be adjusted readily in length.

The forward bob is similar in all respects to the rear bob above described.

Near the forward end of the reach there is 20 supported the bolster H, provided at its ends with grooves for the passage of chains, as is common in this class of sleds. This bolster is adjustable lengthwise of the reach by means of a plurality of holes h to receive the king-bolt. The king-bolt I has its head countersunk in the lower side of the transverse timber and covered by a plate h', the king-bolt passing upward through the timber, through a wearing-plate h², secured to the top of the 25 said timber, through a plate J, attached to the under side of the bolster and serving as a guide for the reach, through one of the holes in the reach, and through the bolster, its upper end being screw-threaded and provided with a nut h³, seated in a cavity in the top of the bolster, the said nut and cavity being covered by a wearing-plate L. The rear bolster is connected with the transverse timber of the rear bob in the same manner. 35

40 The forward end of the reach extends beyond the forward bolster and is provided with a seat M, attached thereto in any suitable manner. This provides a springy support for the seat, and serves to do away with much 45 of the jolting occasioned by going over rough roads.

The transverse timbers of the rear and front bobs are provided with the metallic braces or angle-irons N, which are attached to the under side of said timbers, and, with their vertical portions bearing against the knees of the runners, serve to brace the parts and prevent the runners from tilting out of a perpendicular position.

55 The carrying of the seat on the forwardly-extended end of the reach places the seat in such a position that it is at all times out of the way of the load, so that in turning there is no danger of the driver being injured by 60 the load.

What I claim as new is—

1. In a bob-sled, a reach extended beyond

the front bolster and carrying the seat, substantially as described.

2. The combination, with the reach and 65 bolster adjustable on said reach, of a seat carried by the forward-extended end of the reach, substantially as described.

3. The combination, with the rear and front bobs, of the reach attached at its rear end to 70 the rear bob, the said reach being formed of springy material, with its forward end extended beyond the front bolster, the front bolster, and the seat attached to the forward-extended end of the reach, substantially as 75 described.

4. The combination, with the runner and the transverse timber and the metallic plate B², of the brace-strip passed over the timber and having its ends detachably connected to 80 the runner, substantially as described.

5. The combination, with the runners and the metallic plate thereon, of the brace-strip passed over the metallic plate and provided at its ends with elongated slots through which 85 pass the bolts to secure it to the runners, substantially as and for the purpose specified.

6. The combination of the runners and the transverse timber thereon, the metallic 90 plate B³, the spring brace-strip passed over the end of the transverse timber and the metallic plate, with its ends formed with elongated slots, the bolts passed through said slots and the runner, and the vertical bolts 95 passed through the brace-strip and metallic plate and loosely through the transverse timber and into the knee of the runner, substantially as and for the purpose specified.

7. The combination of the runners and 100 a roll having metallic strips secured to its front edge, the outer ends of which strips are bent backward over the ends of the rolls and form loops adapted to engage corresponding hooks on the forward ends of the runners, 105 substantially as and for the purpose specified.

8. The combination, with the roll and tongue, of the block E⁴, the metallic strip E⁵, passed through said roll and secured in place 110 by nuts, as shown, and the metallic strips secured to the front edge of said roll, the outer ends of which are bent backward and form the loops adapted to engage the corresponding hooks upon the forward end of the runner, 115 substantially as and for the purpose specified.

In testimony whereof I affix my signature in presence of two witnesses.

JOHN GREEN.
